CLAIM

The ornamental design for a car refrigerator, as shown and described.

DESCRIPTION

FIG. 1 is a perspective view of a car refrigerator showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is a partially enlarged view of FIG. 6;

FIG. 9 is a partially enlarged view of FIG. 7; and,

FIG. 10 is another partially enlarged view of FIG. 7.

The broken lines in the drawings disclose unclaimed portions of the car refrigerator and boundaries of isolated views only and form no part of the claimed design.

1 Claim, 10 Drawing Sheets
